UNITED STATES PATENT OFFICE.

JOHN J. TATUM, OF BALTIMORE, MARYLAND.

DRAFT AND BUFFING GEAR.

1,177,062.

Specification of Letters Patent. Patented Mar. 28, 1916.

Application filed July 30, 1909. Serial No. 510,406.

To all whom it may concern:

Be it known that I, JOHN J. TATUM, a citizen of the United States, residing in the city of Baltimore, State of Maryland, have 5 invented certain new and useful Improvements in Draft and Buffing Gear, of which the following is a specification.

The object of my invention is the employment of parts that will attach the draft gear 10 to cars and compose the draft gear for the car in a compact and substantial manner, and at the same time maintain effective qualities for buffing and for draft to pull trains effecting a substantial cushioning to 15 prevent damage to railroad equipment. This attachment is composed of a draw bar, a coupler interlocking with cushion connections, commonly known as draft gear, which is effected by a follower formed with a recess to receive the rear or back end of the coupler barrel or shank, said receptacle having in its walls openings registering with an opening through the coupler shank for a key or cross-bar to pass through. This 20 opening is elongated to permit of the movement of the key forward with the draw bar, while the follower remains stationary or anchored with an opposing stop when draft is being made or the car pulled forward. This 25 follower moves backward with the draw bar when the car is receiving a buff, there being additional space at the back of the keyway in the draft arm and side yoke loop or strap to permit it to slide backward. The 30 draft is effected by the cross key moving forward in the slot of the front follower, at the same time drawing forward the yoke loop or strap which pulls with it the back follower and cross key, while the front follower 35 remains stationary compressing the cushion when buffing, the back follower with the key remains stationary while the front follower is forced down upon the spring or cushion by the inward movement of the coupler.

This draft gear is composed of a front metal follower piece having shoulders to meet with opposing stops and provided with a receptacle to receive the coupler bar. It 40 has a yoke loop or strap with keyways or slots and draft arms with openings to receive the cross keys.

In the drawing, Figure 1 is a top plan view of a draft and buffing gear embodying

my invention, parts being in section; Fig. 2 is a side elevation of the same; Fig. 3 is a perspective view of one of the draft stop castings detached; Fig. 4 is a perspective view of the yoke or side draft gear detached; Fig. 5 is a perspective view of the rear follower; Fig. 6 is a side elevation of one of the draft arms; Fig. 7 is a perspective view of the front follower.

1 represents the car center sills, 2 the car bolster, 3 the end sill and 4 the draft arms of approved construction. I secure to the inner face of each of the draft arms, the draft stop casting 5 provided with lugs 6 which project between the draft arms. This draft stop casting is provided with elongated slots 7 and 8, to be hereinafter referred to.

9 is the rear follower and 10 the front follower. The rear follower is provided with grooves 11 and the front follower is provided on its inner end with a projection or rib 12, in which a slot 13 is formed. The rib or projection 12 forms a stop which is adapted to contact with the stops 6 on the draft stop casting 5. It will be noticed that there is a space between the stops 6 on the stop casting 5 which registers with the slot 13 in the projection 12 on the follower 10. The follower 10 is provided with an elongated slot 14, which, when the follower is in position, registers with the slot 7 in the stop casting 5. The draft arms 4 are provided with elongated slots 15 which register with the slots 7 in the stop casting 5 and the slots 14 in the front follower 10.

16 is a key adapted to pass through the slots in the stop casting 5, the front follower 10 and the draft arms 4, thereby connecting the several parts together. This key is firmly secured in position by means of a cotter or other suitable pin secured in the opening 17, at each end of said key. The rear follower is provided with a slot 18 which registers with the slot 8 in the stop casting 5 and with slots 19 in the draft arms 4.

19^a is a key or bar adapted to pass through the slots in the rear of the draft stop casting, the slots in the draft arms and in the rear follower, whereby the parts are held in assembled position.

20 is a suitable spring cushion mounted between the two followers.

- 21 is a yoke or side draft gear constructed to pass around the rear of the follower block 9 with its arms extending through the grooves 11 in the rear follower, the groove 13 in the front follower and the space between the two stops 6 in the casting 5. This yoke is provided with elongated slots 21^a and 22, through which the keys 19 and 16 are adapted to pass respectively, as clearly shown in Fig. 2.
- 10 23 is the draft buffing stop.
24 is the coupler shank or draw bar.
- In addition to the draft buffing stop 23 I may provide the draft stop casting with a stop lug 25, which will engage the shoulder on the rear follower.
- 20 The front follower 10 is provided with a recess or receptacle, in which the rear end of the draw bar is adapted to fit, said draw bar being provided with a slot adapted, when in position, to register with the slots in the front follower and through which the key 16 may pass, thus firmly locking the coupler or draw bar to the follower block.
- 25 In operation the parts move as follows: In draft, the cross key moves forward in the slot of the front follower at the same time drawing forward on the yoke 21, which pulls with it the back follower by means of the cross key, while the front follower remains stationary, thus compressing the cushion. In buffing, the back follower with its key remains stationary, while the front follower is being forced down upon the spring or cushion by the inward movement or impact of the coupler. The stops 6 co-acting with the stop 12 to limit the outward movement of the front follower, but the draw bar, as above stated, has a still further movement after the follower is at rest, by reason of the elongated slots 14. In buffing, the side yoke, loop or strap remains stationary when in normal position with the key 16 moving inwardly in the elongated slots in the yoke.
- 40 45 The key 16 is relieved of considerable strain by reason of the stop 12 on the follower 10 engaging the stop 6.

The draft and buffing gear constructed according to my invention may be readily detached from the car for repairs and without the inconvenience usually incident to such removal. All that is necessary is to remove the cotter pins from the ends of the keys 16 and 19 and withdraw the keys from the slots of the several members constituting the gear, whereupon the entire gear is dropped of its own weight. With my gear, I have found that it can be removed and replaced in 50% less time and with 50% less men than the gear now in use, especially that type of gear in which the draw bar is connected to the gear by means of bolts.

It will, of course, be understood that changes coming within the scope of the invention as defined in the claims may be

made in the constructions herein shown without departing from the spirit of my invention.

What I claim is:—

1. A draft rigging including a front and rear follower, a cross key connected to each of said followers, both keys to move forward with the draft from normal position, and the key connected to the front follower to move backward while the key connected to the rear follower remains stationary in buffing.

2. In a railway draft gear, in combination a draw bar, draft members having key slots, key stops secured to said draft members, a front follower having key slots, the key extending from the draw bar and slidably connecting the follower to the draw bar, said key also extending into the slots of the draft members the key slots of the follower and draft members being longitudinally extended, whereby the key may slidably operate in said slots on the forward and rearward movement of the draw-bar, the key on the extreme forward movement of the draw-bar 90 engaging against the forward ends of the slots in the follower and in the draft members, the follower substantially simultaneously engaging the said stops.

3. A draft and buffing gear including draft arms having elongated slots, draft stops between the draft arms and having slots coincident with the slots in the draft arms, a front follower having projections to engage said draft stops to limit the forward movement of the follower in draft, a draw bar and a key passing through the draft arms, draft stops, follower and the rear end of the draw bar.

4. A draft and buffing gear including draft arms, draft stops, a yoke, front and rear followers, a rigid buffing stop, slots in the arms, stops and followers registering with each other, a draw bar and keys passing through said slots to connect the followers and yoke, one of said keys connecting the front follower to the rear end of the draw bar.

5. A draft and buffing gear including a follower and a draw bar keyed together, the draw bar having a forward movement relative to the follower when draft is being made.

6. A draft and buffing gear including a front and a rear follower having grooves in their side faces and slots extending from side to side, arms seated in said grooves and connecting said followers, a draw bar, a key rigidly secured to the rear end of the draw bar with its ends projecting through the slots in the front follower and the arms, a key connected to the rear follower and projecting through the slots in the said arms.

7. A draft and buffing gear including draft stops, a front follower limited in its

- forward movement, in draft, by said draft stops, a draft yoke having elongated slots in its forward ends, a draw bar having an elongated slot, and a pin passing through said slots thereby securing said bar, follower, and the front end of the yoke together, said key moving freely in the slot in the said follower while the follower is locked against movement by said stops, whereby the draw bar is free to have further forward movement independent of the said follower.
8. In a railway draft rigging, in combination, draft members, stop members forming front and rear stop shoulders secured thereto, a draw-bar, a key, a compression resisting member, and a pair of followers, both of said followers being provided with forwardly extended slotted arms, the key extending from the draw bar and slidably connecting the arms of the followers to the draw bar, the draft members being provided with transverse slots to receive the ends of the key, the slots in the arms of the front follower and in the draft members being longitudinally extended, whereby the key may slidably operate in said slots on forward and rearward movement of the draw-bar, the key on extreme forward movement of the draw-bar engaging against the forward ends of the slots in the arms of the front follower and in the draft members, the front follower simultaneously engaging the front stop shoulders.
9. In a cushioned draft gear, sills carrying inwardly projecting abutments, a front follower limited in its forward movement by said abutments and projecting forwardly beyond said abutments and provided with a slot, a slotted draw bar, slotted draft links, and a single key located within the slot of the draw-bar, front follower and draft links and connecting them together.
- In testimony whereof I affix my signature in presence of two witnesses.
- JOHN J. TATUM.
